Patented Apr. 1, 1958

182,394

INFANT INCUBATOR

Roy T. Adolphson, Webster Groves, Mo.

Application April 23, 1957, Serial No. 45,868

Term of patent 14 years

(Cl. D83—1)

FIG. 1.

FIG. 2.

Des. 182,394

PAGE 2

FIG. 3.

FIG. 4.

FIG. 5.

FIG. 6.

Fig. 1 is a perspective view of an infant incubator embodying my new design;
Fig. 2 is a front elevational view thereof;
Fig. 3 is a top plan view thereof;
Fig. 4 is a rear elevational view thereof;
Fig. 5 is a side elevational view thereof; and
Fig. 6 is a side elevational view of the side opposite to that shown in Fig. 5.

I claim:
The ornamental design for an infant incubator, substantially as shown.
